UNITED STATES PATENT OFFICE.

HARTWELL L. WILLIAMS, OF RISON, ARKANSAS.

SINGLE-TRIGGER MECHANISM FOR DOUBLE-BARRELED GUNS.

1,142,003.

Specification of Letters Patent.

Patented June 8, 1915.

Application filed February 25, 1913. Serial No. 750,682.

To all whom it may concern:

Be it known that I, HARTWELL L. WILLIAMS, citizen of the United States, residing at Rison, in the county of Cleveland and

5 State of Arkansas, have invented certain new and useful Improvements in Single-Trigger Mechanism for Double-Barreled Guns, of which the following is a specification.

10 This invention relates to firearms and more particularly to single trigger mechanism for double barreled guns.

The main object of my invention is the provision of mechanism whereby both barrels of a gun may be discharged successively and either alternately from right to left or from left to right, the mechanism being under the control of the operator so that he may fire either barrel first as he may desire.

15 A further object is to improve the detail construction of the means for setting the mechanism to fire either barrel, and in this connection to provide a setting member movable from a safety position to a position 20 to fire either one or the other of the barrels as it is desired and to provide indicating means whereby the position of the setting mechanism may be observed.

A still further object is to provide simple 25 and novel mechanism for positively preventing the simultaneous discharge of both barrels when one is discharged, caused by the "involuntary pull" due to the recoil of the gun, and in this connection specifically to provide a catch or stop adapted to be engaged by the hand of the operator and movable upon the recoil of the gun into position to prevent the actuation of the trigger and immediately and automatically movable 30 out of such position upon a rebound of the gun from its recoil.

A still further object is to provide single trigger mechanism for double barreled guns of such simple character that it may be 35 easily assembled or disassembled and which shall be simple and durable in construction, positive in action and applicable to any of the styles of double barreled gun common in use.

40 A further object is to provide safety mechanism for locking the trigger and "selector" mechanism in their downward or inoperative position.

A still further object is to provide for the 45 passage of the tang screw through the lower tang or lock plate, thus eliminating "bridg-

ing" usually resorted to in mechanism of this nature in order to make connection between the upper and lower tang plates, and further to so form the parts that the tightening or loosening of the tang screw shall have no effect upon the operation of the safety locking mechanism, thereby eliminating the necessity of continually adjusting the tang screw.

50 A further object is to provide housing for the actuating mechanism, so constructed as to thereby prevent the mechanism from becoming "wood bound" by the stock or otherwise obstructed.

55 Other objects and advantages will appear in the following description.

My invention is illustrated in the accompanying drawings wherein:

Figure 1 is a side elevation of a portion of a double barreled gun, the frame thereof being broken away to show the trigger actuating mechanism. Fig. 2 is a top view of the construction shown in Fig. 1 but sectioned on the line 2-2 of Fig. 1. Fig. 3 is 60 a like view to Fig. 1 but showing the trigger mechanism in the position assumed when the selector has been set for firing the right hand barrel first and after the trigger has been pulled and the barrel fired, the figure 65 showing the right hand sear as raised and the trigger locked in its raised position by the recoil operated trigger lock. Fig. 4 is 70 a like view to Fig. 3 except that the trigger is shown as released from the raised position, as in Fig. 3 allowing the automatic 75 slide to move forward into a position where its transverse lugs rest under both sears so that at the next actuation of the trigger, both sears will be raised to discharge the unfired or left hand barrel. Fig. 5 is a perspective view of the sears, the trigger, the 80 selective actuating member and the automatic sear actuating member detached from each other. Fig. 6 is a perspective view of 85 the slide, the dogs, the locking lever therefore, the safety lever and the link, the parts being separated from each other. Fig. 6^a is a perspective view of the slide, locking 90 lever and allied parts assembled. Fig. 7 is 95 a perspective view of the selector locking member which forms a housing for the selector and the automatic sear actuating member and the lever for actuating the automatic sear actuating member. Fig. 8 is a 100 perspective view of the recoil operated trigger lock detached from the stock. Fig. 9 is 105 110

a top view of the upper tang and the slide 31 and showing the graduations on the tang coacting with the slide. Fig. 10 is a fragmentary top plan view of the sears and the 5 lower end of the selector in section and showing the selector in position to cause the firing of the right hand barrel, this view also showing in dotted lines the selector in position to cause the firing of the left hand 10 barrel. Fig. 11 is a face view of the lower tang 2 showing the trigger slot in the lower tang, the trigger and the transverse groove 44 in the face of the lower tang.

Corresponding and like parts are referred 15 to in the following description and indicated in all the views of the accompanying drawings by the same reference characters.

My improved single trigger mechanism as before stated is applicable to any of the 20 well known types of double barreled guns now in use and such a gun is illustrated in the figures. In these figures, A designates the barrels of the gun, B the frame, C the stock and D the top snap lever. The stock 25 is connected to the frame B by the usual upper and lower tangs or lock plates, designated respectively 1 and 2. The lower lock plate 2 is formed with a longitudinal slot 3, through which operates the trigger 4. 30 The trigger 4 consists of a vertically disposed, longitudinally extending blade having the usual curved finger piece attached thereto. The trigger is pivoted at its forward end as at 5 in the slot 3 of the lower tang. The free end or back end of the trigger is formed with a notch 6, the purpose 35 of which will be later described.

Mounted upon the tang 2 by means of screws or in any other suitable manner is a 40 trigger safety lock designated 7 and illustrated in Fig. 7. This trigger safety lock is rectangular in form, that is, it forms a casing open at its upper end. The casing comprises a bottom 8 and two upwardly extending sides 9, the upper edges of the sides 45 at their rear end being downwardly beveled as at 10. The forward ends of the sides 9 are formed with projecting ears 11 which are preferably rounded. This trigger safety lock member is attached by screws passing through the bottom 8 into the tang 2 and is 50 of course fixed in position.

Disposed within the housing formed by the member 7 and specifically between the 55 two sides 9 of said member is a sear actuating slide 12 illustrated in Fig. 5. This slide is L-shaped in form, that is, has a downwardly extending forward end 13 and is substantially U-shaped in cross section, the 60 lateral walls of the slide being longitudinally slotted as at 14, and the bottom of the slide being also longitudinally slotted. The downwardly extending nose 13 is preferably solid and at its lower end has the laterally 65 projecting lugs 15 forming a cross bar at the

lower end of the nose. The rear end of the sear actuating slide is closed by a wall 16.

Mounted within the sear actuating slide 12 and longitudinally movable with relation thereto is the selector slide 17. This slide 70 is formed with a longitudinally extending vertical slot 18 for the passage of the tang screw as will be later described and is also formed at its forward end with the downwardly and forwardly projecting nose 19, 75 this nose being preferably solid. The under face of the lower end of the nose is longitudinally grooved as at 20 for the reception of the upper edge of the trigger 4 as illustrated in Fig. 2, the trigger having sliding 80 engagement with the lower end of the nose 19 but the nose and trigger being held from any lateral displacement relative to each other. The rear end of the slide 17 is supported as will be later described. The lower 85 end of the nose 19 is provided with the oppositely projecting sear engaging lugs 21 and 22 which, as will be seen in Fig. 5, are longitudinally spaced from each other so that the lug 21 is disposed in advance of 90 the lug 22. In other words, these lugs 21 and 22 are disposed out of alignment with each other.

Pivotedly mounted within the frame B are the sears 23 and 24. These sears extend longitudinally of the gun and are disposed slightly above the forward end of the tang 2. The forward ends of the sears are beveled and engage with any suitable hammer mechanism.

As illustrated in the drawings, each barrel is provided with a hammer F adapted to engage a cartridge or firing pin. The lower end of the hammer is notched for engagement by the beveled end of the sear. 105 When the sear is raised it is released from the hammer and a hammer spring throws the hammer forward into engagement with the firing pin. The hammer construction is so well known that it needs no special description, and furthermore my mechanism may be varied to suit any particular hammer construction desired.

The sears, of course, extend rearward one 115 on each side of the downwardly extending nose 19 of the selector 17 and each sear is formed upon its inner face with an inwardly projecting lug 25 adapted to be engaged by the lugs 21 or 22 of the selector. The nose 19 of the selector is also provided above the lugs 21 and 22 with laterally projecting safety pins 26 adapted to engage beneath the ears 11 on the trigger safety locking member 7 when the parts are in the safety position 120 illustrated in Fig. 1.

The rear end of the slide 17 of the selector is reduced in thickness and disposed between spaced plates 27 whose upper ends are beveled to form teeth 28. These plates 27 together form oppositely disposed spaced 125

stop dogs or detents, the purpose of which will be later described. The plates are held in engagement with each other and with the slide 17 by means of a screw 27^a and by an oppositely projecting lug 27^b which holds the plates in alignment with the plate 30 of the slide 31.

Passing through the stop dogs or plates 27 is a pin 29, this pin passing through the reduced rear end of the slide 17 as illustrated in Fig. 5, passing through the lower ends of the stop dogs 27 and through the slots 14 of the member 12. Disposed between the plates 27 and held thereto by the screw 27^a 15 and the lug 27^b or in any other suitable manner is an upwardly extending arm 30 which extends through a slot in the upper tang 1 and is connected to a safety slide 31 which moves upon the face of the tang 1, this slide having a rounded protuberant middle portion laterally scored in order to provide for firm engagement with the thumb of the operator. The forward end of this slide is formed with a sight opening 32.

Depending from the upper tang plate 1 is an ear 33 and pivotally connected to this ear is a longitudinally slotted friction stop lever 34. This is longitudinally slotted in its bottom for the passage of the arm 30.

Preferably this stop lever is formed as illustrated in Fig. 6 of one piece of metal bent upon itself to form upwardly extending sides which embrace the arm 30. These sides are formed with a plurality of notches 35, there being three of these notches and these notches coacting with the pointed stop dogs 27. The forward end of the friction stop lever is open for the passage of a pin 36 which depends from the under side of the upper tang

1 and is enlarged at its lower end so as to limit the downward movement of the friction stop lever. A coil spring 37 is disposed around this pin and between the under face of the tang 1 and the upper face of the lever.

The side walls of the lever 34 are cut away at the forward end so as to provide a reduced or flattened portion against which the spring 37 bears. It will be seen that the action of this spring 37 is to force the lever

down with its notches in yielding engagement with the beveled or pointed upper ends of the stop dogs 27. Corresponding to the three notches 35 are three graduations or spaces 38, 38^a and 38^b, these spaces or graduations being marked upon the upper face of the tang 1. The space 38 corresponds to the first of the notches 35 and to the safety position of the slide and therefore within this space is marked the letter S which when the slide 31 is in safety position is displayed through the opening 32.

In the next following subdivision there is the letter R indicating that when the slide is moved to a position where the letter may be seen through the opening 32, the right barrel will fire

upon a pull of the trigger, while in the next succeeding space 38^b, there is marked the letter L which when displayed through the opening 32 shows that the slide 31 has been moved to such position that the left barrel 70 is capable of being fired. The means whereby the firing of the right and left barrel is secured will be seen from further description but it will be obvious that when the slide 31 is moved to the safety position, the pins 75 26 on the downwardly projecting nose 19 of the selector will project laterally beneath the ears 11 and that therefore the selector, and therefore the trigger, will be held from any upward movement and held at "safety". 80

Pivotedly mounted between the rear ends of the sides 9 of the housing and safety lock 7 by means of a pivot screw 39 is an actuating lever 40. This is approximately angular in form and is made of a relatively wide 85 strip of metal which is longitudinally slotted as at 40^a (see Fig. 7). The free end of the actuating lever is outwardly bent or curved as at 40^b and normally bears against the rear end 16 of the sear actuating slide 12. 90 It is curved as at 40^b for the purpose of presenting a good bearing face to the rear end 16 of the slide without regard to the angle of the lever 40. The lever 40 is urged upward and forward by means of a spring 95 41 mounted on an upwardly and forwardly curved post 42 projecting upward from the lower tang 2. It will be seen that the tendency of this spring is to force the lever 40 upward and forward and thereby force the 100 sear actuating slide forward. Further it is to be particularly noted that the slot 14 of the slide 12 is located near the bottom of the slide whereas the free end 40^b of the lever 40 engages the upper portion of the back 16. 105 The sear actuating slide is practically fulcrumed upon the pins 29 projecting from the lower ends of the stop dogs 27 and hence the tendency of the lever 40 urged by the spring 41 is not only to push the sear actuating slide forward but also to rock it upon its fulcrum so as to throw the forward end or nose 13 of the slide downward for a purpose to be later stated. 110

The rear ends of the upper and lower tangs 1 and 2 are connected by means of the tang screw 43^a while a tang screw 43 passes through the middle of the upper tang 1, downward through the slot in slide 17 through the bottom of the sear actuating slide, through the bottom of the trigger safety locking member 7 and into the lower tang 2, and it will therefore be seen that this tang screw 43 acts to guide and steady the slides 12 and 17, and further that these slides are 120 not only guided by the tang screw 43 but by the upwardly projecting arm 30 which passes up through the slot in the upper tang. 125

Slightly in advance of the lower forward corner of the trigger safety locking mem- 130

ber 7, the lower tang plate 2 is transversely grooved as at 44. This groove is intersected by the longitudinal slot in the tang 2 through which the trigger 4 operates. The rear end 5 of the trigger 4 is cut away as at 6 so as to provide a shoulder 45. This cutaway portion 6 approximately coincides with the groove 44 and the lugs 15 of the nose 13 of the sear actuating slide 12 normally rest in 10 this groove 44 as illustrated in Fig. 1. When the trigger is pulled, however, as illustrated in Fig. 3, the forward end of the sear actuating slide will be raised against the force of the spring 41 until such time as the lugs 15 15 lift beyond the upper face of the tang 2, whereupon the spring 41 acting through the lever 40 will force the sear actuating slide forward and beneath the sears as will be later explained.

20 It was stated above that the cutaway portion 6 of the trigger 4 approximately fitted and corresponded with the shape of the groove 44. This is true, with this exception, that the back end or shoulder 45 of the cutaway portion 6 does not extend to or even 25 with the adjacent wall of the groove 44, that is, the cutaway portion 6 is longer than the width of the groove 44.

The lower portion of the nose 13 of the 30 sear actuating slide when resting in the groove 44 of the tang 2, also rests upon the top edge of the trigger 4 and consequently will be raised up and out of the groove 44 when the trigger is raised. Thus when the 35 trigger is raised, as shown in Fig. 3, the forward end of the automatic sear actuating slide is freed from the groove 44 and this allows the forward end of the slide to move forward in the cutaway portions 6 until the 40 lower end of the nose 13 strikes the shoulder 45. This shoulder as previously stated is disposed forward of the groove 44 and therefore since the nose 13 is resting against the shoulder 45, the lugs 15 will have moved 45 forward and out of line with the groove 44 extending so that when the trigger is released or allowed to descend, the lugs 15 and the nose 13 will strike the top surface of the tang 2 forward of the groove 44 50 which stops their downward movement, causing them to slip over the shoulder 45 of the trigger as the trigger descends to its downward position. This now leaves the sear actuating slide free to move forward 55 under the influence of the lever 40 until the lugs 15 rest under the sears 23 and 24 as in Fig. 4 and since the nose 13 rests on top of the trigger 22, if the trigger be again raised while the sear actuating slide is in this position, both of the sears will be raised. The 60 operation of this part of the invention is as follows: In the position shown in Fig. 1 which is the safety position, the slide 31 is at its safety position with the letter S dis-

played through the opening 32. As a consequence 65 the dogs 27 are engaged with the rearmost notches 35. The slide 17 is drawn rearward so that the lugs 21 and 22 are rearward of the corresponding lugs on sears 23 and 24, the pins 29 at the rear ends of the 70 slots 14 and as a consequence the sear actuating slide 12 is held in its rearmost position forcing back the lever 40 and compressing the spring 41. At this period the lugs 15 75 on the nose 13 of the sear actuating slide 12 are disposed within the groove 44, being held therein by the downward pressure upon the forward end of the sear actuating slide caused by the rotative action of the lever 40 as previously stated. The trigger is, of 80 course, forced down and held in its downward position by the downward force exerted upon the forward end of the sear actuating slide. Inasmuch as the selector 17 is drawn rearward, the safety pins 26 are extended beneath the locking lugs 11 of the housing and trigger safety lock 7, thereby locking the trigger. If now it is desired to 85 fire one or the other barrel of the gun, the slide 31 is shifted forward. If it is desired 90 to fire the right barrel, the slide 31 is shifted forward until the letter R is displayed through the opening 32. This shifts the selector forward and also of course shifts the pins 29 forward in the slot 14 so as to 95 permit the forward movement of the sear actuating slide when released. The forward movement of the selector carries the safety pins 26 from underneath the lugs 11 and also carries the lug 21 beneath the lug or 100 shoulder 25 on the sear 23, that is, the sear for the right hand barrel. In this position, as is seen by reference to Fig. 10, the lug 22 will be behind the lug 25 of sear 24, and upon a vertical movement of the nose of the 105 selector the sear 24 will not be actuated. Upon pulling the trigger, the trigger will move upward against the force of spring 41 110 which will shift the selector upward and the lug 21 will engage with the lug 25 on sear 23 and trip the sear 23, tripping the hammer in the usual manner. As soon as the trigger rises, it will lift the nose 13 and the lugs 15 out of the groove 44 and the slide will move forward until the lugs 15 115 strike against the shoulder 45 on the trigger. When now the trigger is released and moves downward, the spring 41 acting upon the lever 40 will shift the slide still farther forward so as to carry the lugs 15 beneath both 120 of the sears. If now the trigger be again actuated it will lift the nose 13 of the sear actuating slide and the lugs 15 will throw up both sears, thus tripping the hammer which was not tripped before, that is, the 125 left hand hammer. Precisely the same operation occurs if the slide 31 be shifted forward so that the letter L is displayed

through the opening 32, only in this case as will be plain from Fig. 10, the nose 19 of the selector slide 17 will be moved so far forward that while the lug 22 will come beneath the lug 25 of the sear 24, the lug 21 will be shifted to a point in advance of the lug 25 of sear 23 so that when the selector rises under the impulse of the trigger, the lug 22 will engage with sear 24 but the lug 21 will escape the lug 25 of sear 23 and the left hand barrel will be fired. Here again upon a second actuation of the trigger the other barrel will be fired.

In order to provide mechanism whereby the firing mechanism may be returned to its safety position if it is in a firing position and the gun is broken or the top snap D is turned so as to permit the opening or breaking of the gun, I provide the return safety lever designated 46 which is pivotally connected at its lower end to the lower tang 2 as at 47. The upper end of this lever is pivotally connected as at 48 to parallel rods or links 49 which are spaced apart sufficiently to permit the passage of the tang screw 43 and which extend rearward and at their rear ends are pivotally connected by a pin 50 to an ear 51 projecting from the arm 30. The forward edge of the lever 46 intermediate its ends is thickened or provided with a curved faced shoulder 52 which is disposed immediately opposite to the locking pin 53 of any ordinary or usual construction and which is connected to the top snap D in such manner that when the top snap is rotated to an angular position with relation to the frame and stock so as to permit the gun to be opened, the locking pin will be protruded. This breech lock mechanism is a common construction and forms no part of my invention and therefore requires no further description. The object of curving the face of the shoulder 52 is to present a proper bearing surface at all times to the breech lock 53. It will be seen that when the mechanism is in the position for firing either the right or left hand barrel, the return lever 46 will have moved forward and toward the breech lock 53. Hence when the breech lock is actuated by the top snap D it will move rearward and will strike the shoulder 52 of the lever 46 and will force this lever backward. As the lever 46 is connected to the lower extension or arm 30 of the safety slide 31, the firing mechanism will also be moved backward into safety position. It will, of course, be understood that the movement or stroke of the lever 46 is to be regulated so that the upper end of the lever will travel rearward a distance sufficient to carry the arm 30 and the slide 31 to safety position. This may be accomplished by lengthening or shortening this lever 46.

It has been found by tests that where a single trigger is employed to discharge both barrels of a gun, the recoil of the gun, when one barrel is fired, will cause what is termed an "involuntary pull" on the trigger by the operator, thereby firing the other barrel unintentionally. An explanation of this action is that the recoil of the gun carries the gun backward and against the shoulder of the gunner, causing the trigger finger to move forward, so to speak, relatively to the trigger, but in reality the trigger is moved backward with the backward movement of the gun on the recoil, therefore moving the trigger away from the trigger finger and allowing its release. At this instant the resistance of the shoulder of the operator and the elastic return of the muscles of the shoulder to their normal position, causes the gun to rebound quickly and by this rebound the finger is again thrown against the trigger causing the said involuntary pull and causing the other barrel to be fired. To positively prevent this involuntary pull, I have provided mechanism operated by and in absolute accordance with the recoil and rebound of the gun whereby the trigger is locked for an instant and then again released.

The trigger as shown in Fig. 5 is provided with a recess 54 at its rear end adjacent to the finger piece and beneath the recess 6. This recess is so located that it is normally below the level of the lower face of tang 2 but when the trigger is raised, the longitudinal wall of the recess is brought flush with the face of the tang. Mounted upon the under face of the tang 2 is a slide bolt or lock 55 which is formed with a downward extension 56. The bolt or lock is rectangular in form but the extension is in the form of a relatively thin vertically disposed web though made integral with the bolt. The extension passes through and operates within a slot 57 formed in the downwardly extending portion 58a of the trigger guard 58 and formed integral with this extension but disposed upon the outer face of the trigger guard is a transversely extending plate 59 which is curved to conform to the curved portion 58a of the trigger guard and then extends longitudinally along and bears against the under face of the tang 2 and the under face of the stock as at 60. This portion 60 which is long enough to provide a full bearing face for the fingers of the operator is roughened, knurled, serrated, or otherwise formed so that the fingers of the operator may secure a good grip thereon. This portion 60, which, as before remarked, is integrally connected with the portion 56 and the lock 55, is longitudinally shiftable in relatively small limits along the under face of the stock and tang provided that the trigger

is raised. When the trigger is raised and the lock shifted in one direction toward the muzzle of the gun, the locking member 55 will be slipped into engagement with the notch or recess 54. When it is shifted toward the butt of the gun, however, the locking member will be drawn out of engagement with the recess or notch 54. When it is in engagement with the recess or notch 54, the trigger will be held from any movement in either direction but as soon as it has slipped out of the notch, the trigger may be moved as usual. This locking member can only be shifted when the trigger is raised as when the trigger is not raised, as in Fig. 1, the end of the trigger protrudes below the level of the under face of the tang 2 and locks the locking member securely in its rearward position. The hand of the operator, due to the recoil, forces the locking member into engagement with the notch or recess 54 only when the trigger is raised and a shot fired which produces recoil. The trigger is intended thereby to be locked for an instant in its raised position during the instant in which the finger is away from the trigger due to the backward movement of the gun on the recoil.

The sliding locking member 55 is provided with a longitudinally extending slot 61, the side walls of which are shouldered or rabbed as at 62, and disposed in this slot and having engagement with the longitudinal shoulder 62 is a block 63 held in place by a screw 64 which passes into the tang. The block 63 may be held in place by means of the screw 64 but in guns which will permit, it is preferable to allow the tang screw 43 to extend through the lower tang 2 and into the block 63 as illustrated in Fig. 3. The numeral 64, therefore, indicates the extremity of the tang screw.

The knurled, matted or serrated extension 60 or sliding portion has at its rear end an upwardly extending lug 65 which fits in a longitudinal slot 65^a formed in the rearward extension of the trigger guard 58, this extension being designated 66. This extension of the trigger guard is attached to the lower tang 2 and extends beyond the length of the tang 2 and is held to the stock by a screw 67. The upwardly extending lug 65 is perforated to receive a transverse pin 68 which when fitted in the lug 65 fastens the rear end of the matted extension 60 to the extension of the trigger guard but leaves the extension 60 together with the sliding locking member 55 free to slide back and forth. It will be understood that there are many methods which may be employed to support the extension 60 and bring about the same results as described.

It is to be noted that the slot 65^a is narrowed at its rear end so as to fit snugly the

lug 65. The lug 65 moves forward only a relatively short distance. It does not therefore move far enough forward to pass entirely out of the narrowed portion of the slot. As the pin 68 is located at the rear end of the lug 65, it maintains its full bearing upon the upper face of the trigger guard extension 66 at all positions of the lug 65. It will, of course, be understood that the stock should be slotted to receive the lug 65 and to allow its forward movement, and that the stock should be recessed to receive pin 68 and allow its movement forward with lug 65. The pin 68 acts as a key pinning the extension 60 to the under face of extension 66 but allowing the longitudinal movement of the extension 60 as the pin 68 is free to slide upon the face of extension 66.

I want it especially understood that instead of being matted or knurled, the extension 60 may be constructed with "hog backs" or curved recesses, curved to fit the fingers or may be formed in any other manner to insure a reliable connection between the extension 60 and the fingers of the operator's hand when the hand grasps the stock in a natural way so as to insure the backward or forward movement of the sliding locking member 55 upon the recoil and rebound of the gun.

In order that it may not be necessary to rely upon the rebound of the gun alone to move the recoil trigger locking slide 55 back and out of notch 54 of the trigger after a shot has been fired, a spring may be provided and so placed that its force will be exerted backward and on the extension 60 so that when the trigger locking slide moves forward, due to the recoil it will move against the force of this spring and the spring will act to force the slide backward again to its released position after the force of the recoil is spent. In Fig. 1, I show one form of this spring. In this figure, 70 designates a coil spring which is disposed in a recess 71 formed upon the inner face of the extension 60 and in a slot formed in the extension 66 of the trigger guard. This spring bears at one end against the rear end of the lower tang 2 and at its other end bears against the upright lug 65. It will be seen that as the coil spring abuts against the rear end of the tang 2 its force will be exerted upon the lug 65 and that therefore when the trigger locking slide moves forward it will be against the force of this spring and that after the force of the recoil is spent, the spring will return the slide to its rearward position carrying the locking member 55 out of engagement with the notch 54. I do not wish to be limited, however, to the use of this mechanism for normally holding the locking bolt or slide 55 out of engagement with the notch 54 as a

spring catch or a friction catch or any other suitable catch may be provided which will hold the recoil trigger locking slide in its position firmly enough to insure its remaining in its rearward position until it is forced forward and out of the catch by the recoil of the gun. It will be seen in Fig. 1 that the rear end of trigger 4 when the trigger is down or in its normal position holds or locks the recoil slide firmly in its rearward position. The friction catch mentioned above would hold the slide in its rearward position before the operator releases the trigger and after having fired one barrel, that is, would hold the slide in its rearward position when the trigger is raised.

The operation of the mechanism which I have described for locking the trigger upon the recoil is as follows: In Fig. 3 the mechanism is shown as being set to fire the right hand barrel, the left hand barrel having been fired. Assuming that the right hand barrel has not been fired although the mechanism has been so set, then immediately that the trigger is pulled, there comes a recoil of the gun. By reference to Fig. 3 it will be seen that the recoil has forced the gun back and left the trigger locked in its raised position while the trigger finger has moved forward, that is to say, the gun has moved backward leaving the trigger finger forward. Now the rebound comes instantly, throwing the gun forward again. If the trigger had been allowed to release, the trigger finger would strike it and raise it again as the gun moved forward on the rebound but the locking member has kept the trigger locked in its raised position so that when the gun again moves forward on the rebound, the finger does not find the trigger released but is forced on back and against it in its raised position and strikes it just at the moment that the locking member moves out of the recess 54, due to the gun moving forward on the rebound. As the hand of the operator grasps the matted extension 60 when the gun moves forward on the rebound, the locking member will be moved out of the recess 54. This now leaves the finger against the unlocked trigger in its raised position and since the recoil and the rebound are both over the trigger is free to be released for the next shot. It is particularly to be noticed at this point that no direct trigger spring is used. The downward force of the sear springs is relied on for this purpose. When the gun is fired or either sear is raised, it will be noted that the sear offering a resistance due to its spring exerts a downward force upon the lugs 21 or 22, as the case may be, thereby transmitting this downward force to the selector which rests on top of the trigger and forces the trigger downward. When on safety, the trigger

and selector are held down by the safety lock. When off of safety one or the other of the lugs 21 and 22 rests under one or the other of the shoulders 25 of the sears.

In some single trigger mechanisms where it is desired that only one sear be raised in firing the second shot instead of both sears being raised, as in the gun illustrated in connection with my invention, a cam surface is constructed upon the hammers below the notch where the sears engage. This cam surface when the hammer is released, comes in contact with and bears or presses down upon the end of the corresponding sear keeping the sear in a raised position until the hammer is again cocked. Therefore the sear of the discharged barrel is left in a raised position leaving the sear of the loaded barrel to be raised alone at the next pull of the trigger. This construction of hammer and sear forms no part of my invention and I have not illustrated it, but it will be perfectly well understood that the principle of my invention may be applied to this form of hammer where the results as described are desired, but in all these cases a direct trigger spring is rendered necessary in lieu of the indirect trigger spring created by the action of the sear springs.

The operation of my invention is as follows: In Fig. 1 the mechanism is seen at safety, from which position if it be desired to fire the right hand barrel first, the safety slide 31 is shifted forward until the selector stop dogs rest in the middle notch of the notches 35 or first notch forward from the safety notch of the friction lever 34 as shown in Fig. 3. This will place the lug 21 of the selector under shoulder 25 of the sear 23. Therefore when the selector is raised by the trigger, the sear 23 will also be raised as in Fig. 3 and the right hand barrel will be discharged. The lug 22 which actuates lug 25 upon the left hand sear 24 has not moved far enough forward to rest under the shoulder 25 and therefore misses it as the selector is raised to fire the right hand barrel and leaves the sear 24 of the left hand barrel undisturbed. When the trigger is raised as is previously described, it also raises and releases the forward end of the sear actuating slide 12 from the groove 44 and allows the slide to move forward against the shoulder 45 of the trigger. Therefore, when the trigger is released, the nose 13 of the automatic slide 12 strikes the top surface of the tang 2 and slips along over the shoulder 45 of the trigger as the trigger moves on down until the top is level with that of tang 2. The automatic slide being acted upon by the lever 40 and under the influence of spring 41, moves forward until the transverse lugs 15 lie beneath both sears, as in Fig. 4. Therefore, when

the trigger is again pulled, the automatic slide will be again raised and with it both sears. Hence the remaining cocked hammer will be released, thereby firing the left hand barrel. The recoil trigger locking mechanism will fulfil its functions as previously described. After either one or both barrels have been fired, the mechanism may be brought back to safety by sliding the safety 10 slide 31 back to its safety position, or if the gun is reloaded or broken, in which instance the top snap D is turned, the mechanism will be automatically placed in its safety position due to the action of the breech lock 53 15 upon lever 46 of the automatic safety return mechanism previously described. To fire the left hand barrel first, the slide 31 is moved to its extreme limit of forward movement in which position the selector stop 20 dogs 27 will rest in the last notch 35 of the friction lever 34. In this position the lug 22 comes in contact with shoulder 25 of the sear 24, whereby when the trigger is pulled it raises the same, releasing the hammer and 25 firing the left hand barrel. In this instance, the lug 21 which actuates the right hand sear will have moved forwardly and beyond the shoulder or lug 25 of the right hand sear, thereby leaving the right hand sear undisturbed. The automatic slide when the 30 left hand barrel is fired acts identically the same as previously described for firing the right hand barrel, as does also the recoil trigger locking mechanism.

35 It is particularly pointed out that no flat springs are used in the mechanism. Coil springs are used instead and only two coil springs are necessary, namely, the spring 37 and the spring 41.

40 It is particularly pointed out that the recoil trigger locking mechanism is a very important and integral part of the single trigger mechanism as no single trigger mechanism can be made practical or have 45 any value in which the "involuntary pull" before referred to is not compensated for. The overcoming of this involuntary pull is a vital part of the problem of forming a single trigger mechanism for double barreled guns.

50 What I claim is:

1. A single trigger mechanism for double barreled guns including sears, one for each barrel, a trigger constantly out of engagement with the sears, a sear tripping member 55 separate from but operatively engaged with the trigger normally lying in safety position to prevent movement of the trigger and manually shiftable from a safety position 60 into a position of operative engagement with either sear, a sear tripping member separate from the trigger and from the manually shiftable sear tripping member but coacting therewith and in operative engagement with

the trigger and automatically movable into 65 position to trip an untripped sear upon a single actuation of the trigger, and an adjusting member mounted upon the upper face of the gun and operatively connected to the first mentioned sear tripping member to 70 shift the latter.

2. A single trigger mechanism for double barreled guns including sears, one for each barrel, a single trigger, a single sear tripping member in operative engagement at all 75 times with the trigger and manually movable into a position to operatively engage with either sear, a separate but coacting sear tripping member automatically movable into position between both of the sears and the 80 trigger upon a single actuation of the trigger, and an adjusting member mounted upon the upper face of the gun and operatively connected to the first named sear tripping member to shift the latter.

3. A single trigger mechanism for double barreled guns including sears, one for each barrel, a trigger, a single sear tripping member manually slidably longitudinally into position between either one of the sears and 90 the trigger, a separate but coacting sear tripping member disposed in engagement with the trigger and slidably into position between the trigger and both of said sears, means urging the last named tripping member 95 into such position upon a single actuation of the trigger, and an adjusting member mounted upon the upper face of the gun and operatively connected to the sear tripping member to shift the latter.

4. A single trigger mechanism for double barreled guns including sears, one for each barrel, a trigger, a manually shiftable sear tripping member in operative engagement at 105 all times with the trigger and manually movable longitudinally into a position of operative engagement with either sear or into a position out of engagement with both sears, and means for preventing a sear tripping movement of the trigger and said member when in the latter position.

5. A single trigger mechanism for double barreled guns including a trigger safety lock, a trigger locking member having a projecting lug at its forward end, sears, one for 115 each barrel, a trigger and a sear tripping member in operative engagement with the trigger and manually movable longitudinally from a safety position into a position to have operative engagement with either sear or into a safety position out of operative engagement with both sears, and a projection upon the sear tripping member engaging beneath the lug on the trigger locking member when the said tripping member 120 is in its safety position.

6. A double barreled gun including a plurality of sears, a single trigger disposed be-

tween the planes of the sears and constantly out of engagement therewith, and a selector 5 separate from but in the same plane and having operative engagement with the trigger and having staggered lugs disposed on its opposite sides and on the same level relative to each other, said selector being manually movable longitudinally from a safety position, in which it prevents movement of 10 the trigger, into position to engage either sear, the lug on the opposite side from the sear engaged being out of line with and missing its sear on an actuation of the trigger and effecting the discharge of either barrel first as desired.

7. A double barreled gun including a pair of sears, each having projecting lugs, a trigger disposed between the planes of the sears and constantly out of engagement therewith, 20 a selector supported at all times by the trigger between the sears and having oppositely projecting lugs disposed in staggered relation and in the same plane, means disposed upon the upper face of the gun for shifting 25 the selector from a safety position, in which it prevents movement of the trigger, into position to bring one or the other of its lugs into position beneath one or the other of the lugs on the sears, and a sear tripping 30 member automatically movable into position to trip an untripped sear upon a second actuation of the trigger and to be thrown into operative position after one barrel has been fired.

35 8. A double barreled gun including a pair of sears each having an inwardly projecting lug, a trigger constantly out of engagement with the sears, a selector supported by the trigger and extending upwardly therefrom 40 between and beyond the sears and having oppositely projecting integral lugs disposed in staggered relation but located on the same level relatively to each other whereby in one position of the selector one of the lugs 45 will engage one of the sear lugs but the other lug on the selector will be out of engagement with the lug upon the other sear, means for automatically tripping an untripped sear upon a second actuation of the trigger, said 50 means being thrown into operative position after one barrel has been fired, and means disposed upon the upper face of the gun for shifting the selector into position to bring one or the other of its lugs beneath one or 55 the other of its sears.

9. A double barreled gun including a pair of sears, each having an inwardly projecting lug, the lugs of the two sears having staggered relation, a trigger, a selector supported 60 by the trigger and longitudinally movable beneath said sears and having oppositely projecting lugs offset from each other whereby in one position one of the lugs on the selector will engage one of the sear lugs

but the other lug will be out of engagement 65 with its corresponding sear lug and in a second position the last named sear lug will engage with the corresponding lug on the selector but the other selector lug will be out of engagement with the corresponding sear 70 lug, a sear tripping member movable into position between both of said sears and the trigger, and means for automatically shifting said last named sear tripping member into operative position upon a second single 75 actuation of the trigger.

10. A double barreled gun including a plurality of sears, a trigger, a selector resting upon the trigger and movable longitudinally from a safety position to a position to 80 engage either sear to effect the discharge of either barrel, a longitudinally movable slide mounted upon the exterior of the gun, manually actuatable and operative connections between the slide and the selector, and a sear 85 tripping member adapted to be shifted into position between both sears and the trigger, and means for automatically shifting said sear tripping member into operative position upon a second or after a first single actuation 90 of the trigger.

11. A double barreled gun including a plurality of sears, a trigger and a selector resting upon the trigger and movable from a safety position into a position to engage 95 either sear to effect the discharge of either barrel, a slide mounted upon the exterior of the gun, operative connections between the slide and said selector, a stop lever having a plurality of notches, a dog forming 100 part of said operative connections and co-acting with said notches, and means yieldingly forcing the lever into engagement with the dog whereby to hold the slide and selector set at any adjusted position. 105

12. A double barreled gun including a plurality of sears, a trigger and a longitudinally movable selector resting upon the trigger and movable from a safety position to a position to engage either sear to effect the 110 discharge of either barrel, a member mounted in the path of movement of the selector and engaging with the selector to hold it and the trigger in a lowered position when the selector is in a safety position, and manually actuatable means for shifting the selector from the safety position and out of engagement with said member. 115

13. A double barreled gun including a plurality of sears, a trigger and a selector 120 operatively engaged by the trigger movable from a safety position into a position to engage either sear to effect the discharge of either barrel, means for locking the selector and the trigger in a lowered position when 125 in a safety position, a slide operatively connected to the selector to shift the same, a spring actuated notched lever mounted

above the selector, and a dog carried by the slide and engageable with the notches in said lever whereby to yieldingly hold the selector set in any adjusted position.

- 5 14. A double barreled gun including a plurality of sears, a trigger and selector in operative engagement at all times with the trigger and manually movable from a safety position into a position to operatively engage either sear, a sear tripping member having a portion disposed rearward of the selector and automatically movable into position beneath both of the sears upon a single actuation of the trigger.
- 10 15. A double barreled gun including a plurality of sears, a trigger, a sear tripping selector in operative engagement at all times with the trigger and manually movable into a position to operatively engage with either sear, a longitudinally movable sear tripping member having oppositely disposed lugs at its lower end movable with the member in a path beneath both of the sears and resting upon the trigger, means for detaining the 25 tripping member rearward of the sears until the trigger is actuated, and means for automatically shifting said sear tripping member forward into operative position upon a single actuation of the trigger.

- 30 16. A double barreled gun including a plurality of sears, a trigger, a sear tripping selector resting upon the trigger and movable from a safety position into a position to engage either sear to effect the discharging 35 of either barrel, a sear tripping member having a body portion formed with opposed walls between which the selector is longitudinally shiftable and having oppositely projecting lugs moving in a path beneath 40 both sears, spring actuated means urging the sear tripping member to its sear engaging position, and means for holding the sear tripping member in inoperative position but permitting the sear tripping member to 45 move forward into an operative position upon a single actuation of the trigger.

17. A double barreled gun including a plurality of sears, a trigger, a manually movable selector operatively engaged by the 50 trigger and longitudinally movable from a safety position to a position to engage either sear to effect the discharge of either barrel, said selector being longitudinally slotted, and a tang screw passing vertically through 55 the selector and forming a guide for the same.

18. A double barreled gun including a plurality of sears, a trigger and a selector operatively engaged at all times by the trigger and manually movable longitudinally 60 from a safety position to a position to engage either sear to effect the discharge of either barrel, said selector being longitudinally slotted, a sear tripping member dis-

posed beneath the selector and longitudinally movable into a position beneath both of said sears upon a single actuation of the trigger, said sear tripping member being longitudinally slotted, and a tang screw passing vertically through the slots of the 70 selector and the sear tripping member and guiding the same.

19. A double barreled gun including a frame having upper and lower tangs, a plurality of sears, a trigger, a selector operatively engaged by the trigger and longitudinally movable between the tangs from a safety position into a position to engage either sear to effect the discharge of either barrel, said selector being longitudinally 80 slotted, a sear actuating sliding member having lugs, said member being movable into position upon a single actuation of the trigger to bring said lugs between both of said sears and the trigger, said sear actuating member embracing and guiding the selector and being longitudinally slotted, means urging the sear actuating member into its operative position, means holding the sear actuating member in an inoperative position until the trigger has been actuated, and a tang screw passing vertically from the upper tang through the slots of the selector and the sear actuating member and engaging the lower tang.

95 20. A double barreled gun including a plurality of sears, a trigger, a sear operating selector operatively engaged with the trigger and longitudinally movable from a safety position to a position to engage either sear to effect the discharge of either barrel, said selector comprising a longitudinally slotted body portion having at its forward end a downwardly projecting nose provided with laterally projecting lugs 100 adapted to engage said sears and a sear actuating sliding member having a body portion embracing the body of the selector and having at its forward end a downwardly projecting nose provided with oppositely 105 disposed lugs adapted when in operative position to be disposed between the trigger and both of said sears, manually actuatable means for shifting the selector from a safety position to an operative position, 110 spring actuated means urging the sear actuating member from an inoperative to an operative position, and means normally holding the sear actuating member in a safety position but permitting the forward 115 movement of the sear actuating member upon a single actuation of the trigger.

120 21. A double barreled gun including a plurality of sears, a trigger and a sear actuating selector comprising a body having a downwardly projecting nose formed with laterally projecting lugs, said selector being movable from a safety position into a posi-

- tion to cause the lugs to engage with either sear to effect the discharge of either barrel, a tang disposed below the sears and having a transverse groove and also formed with 5 a longitudinal trigger slot intersecting said groove, the trigger having a portion moving in the notch and a sear actuating member having a body portion embracing the body of the selector and having a nose projecting 10 downward behind the nose of the selector and formed with oppositely disposed lugs adapted to rest in said groove in the tang but to be lifted therefrom by the raising of the trigger, and spring actuated means 15 urging the sear actuating member forward from an inoperative to an operative position and urging the forward end of the sear actuating member downward whereby the sear actuating member shall be shifted forward 20 to an inoperative position when its lower end is lifted from the groove by the lifting of the trigger.
22. A double barreled gun including a plurality of sears, a tang disposed beneath the sears and having a longitudinal trigger slot and a transverse groove upon its inner face intersecting said slot, a trigger pivotally mounted within said slot and having its rear end disposed beneath said groove, the 30 upper edge of the rear end of the trigger being cut away to an extent slightly greater than the width of the groove, a selector operatively engaging the trigger at all times and manually movable from a safety position to a position to engage either sear to effect the discharge of either barrel, a longitudinally shiftable sear actuating member comprising a body having a downwardly projecting nose engaging in said tang 35 groove, and spring actuated means urging the sear actuating member forward and downward.
23. A double barreled gun including a lower tang formed with a longitudinally extending trigger slot and a transversely extending groove upon its inner face intersecting said slot, a trigger pivoted in said groove and cut away at its rear end to a depth greater than the width of the groove, a housing and trigger locking member disposed upon the tang and including spaced vertically extending walls, the forward upper corners of said walls being each provided with a forwardly projecting lug, a plurality 50 of sears disposed above the tang, a sear actuating member slidably mounted between the walls of said housing and longitudinally slotted at its rear end, said member having a downwardly projecting nose at its forward end formed with oppositely disposed lugs forming a cross bar engageable in the groove in the tang and resting normally upon the cutaway portion of the trigger, a selector having a body portion disposed in 55 and sliding upon the body of the sear actuating member and having a downwardly and forwardly projecting nose formed at its lower end with oppositely projecting offset lugs and also provided with oppositely disposed projections engageable beneath said 60 lugs on the housing when the selector is in its rearward or safety position, a pin passing through the body of the selector and into the slots in the trigger actuating member, an arm operatively connected to the rear end of the selector, a slide upon the exterior of the gun and connected to said arm, latching means for yieldingly detaining the selector and slide in any adjusted position, a lever engaging with the upper rear end 65 of the sear actuating member, and a spring urging said lever forward.
24. A single trigger mechanism for guns including a plurality of sears, shiftable sear selecting mechanism manually movable from a safety position out of engagement with both sears into an operative position in engagement with either sear, a top snap, coacting breech locking mechanism, and means actuated by a movement of the breech locking 70 mechanism to an unlocking position shifting the selecting mechanism to a safety position.
25. A double barreled gun including a plurality of sears, a trigger, a sear actuating selector resting upon the trigger and movable from a safety position into a position to engage either sear to effect the discharge of either barrel, a top snap, coacting breech locking mechanism, and means actuated by a movement of the breech locking 75 mechanism to an unlocking position shifting the selector to a safety position.
26. In a double barreled gun, a breech locking mechanism including a longitudinally shiftable member and a top snap for actuating said member and operatively connected to the member to shift the latter rearward when the top snap is turned out of parallel relation to the barrel, a plurality of 80 sears, a trigger, a selector operatively engaged with the trigger and movable longitudinally forward from a safety position into a position to engage either sear to effect the discharge of either barrel, a safety lever 85 pivoted at its lower end and extending upward in front of the movable member of the breech locking mechanism and adapted to be engaged and shifted by said member when the member is moved rearward, and a link connecting said lever to the selector.
27. In a double barreled gun, breech locking mechanism including a longitudinally shiftable member and a top snap for actuating said member and operatively connected to the member to shift the latter rearward when the top snap is turned out of parallel relation to the barrel, a plurality of sears, a 90

trigger, a selector operatively engaged with the trigger and movable longitudinally forward from a safety position into a position to engage either sear to effect the discharge of either barrel, a safety lever pivoted at its lower end and extending upward in front of the movable member of the breech locking mechanism and adapted to be engaged and shifted by said member when the member is moved rearward, a link connecting said lever to the selector, and mechanism for yieldingly latching the selector in its rearmost safety position.

28. In a double barreled gun, breech locking mechanism including a longitudinally shiftable member and a top snap for actuating said member and operatively connected to the member to shift the latter rearward when the top snap is turned out of parallel relation to the barrel, a plurality of sears, a trigger, a selector operatively engaged with the trigger and movable longitudinally forward from a safety position into a position to engage either sear to effect the discharge of either barrel, a safety lever pivoted at its lower end and extending upward in front of the movable member of the breech locking mechanism and adapted to be engaged and shifted by said member when the member is moved rearward, a link connecting said lever to the selector, and mechanism for yieldingly latching the selector in its rearmost safety position and in position to engage the sear of either barrel.

35 29. In single trigger mechanism for guns, the combination with a trigger, of a sliding locking member disposed at the rear end of the trigger and adapted to lock the same against movement when shifted relatively forward, said member including a grip adapted to be engaged by the hand of the operator.

30. In a single trigger mechanism for guns, the combination with a lower tang and a trigger having a longitudinally extending notch at its rear end, of a locking member slidably mounted upon the tang and adapted to engage in said notch when in a forward position, said locking member including an extension disposed beneath the stock and engaged by the hand of the operator.

31. In a single trigger mechanism, the combination with a lower tang, a trigger having a notch at its rear end and a trigger guard extending beneath the trigger and then extending rearward along the tang, said trigger guard being formed with a vertical slot, of a locking member slidably mounted upon the under face of the tang and shiftable forward into engagement with the notch of the trigger, said locking member having a portion thereof extended through the slot of the trigger and then extended along and parallel to the face of the

trigger guard and adapted to be gripped by the hand of the operator.

32. In a gun, the combination with a stock and a trigger having a notch at its rear end, of a recoil operated locking member freely slidable upon the stock into engagement with the notch of the trigger, said member having a portion adapted to be gripped by the hand of the operator.

33. In a gun, the combination with a stock and a trigger having a notch at its rear end, of a recoil locking member having a rearwardly extending hand grip freely slidable upon the stock and adapted to be gripped by the hand of the operator to cause the engagement of the locking member with the notch of the trigger upon the recoil of the gun.

34. In a gun, the combination with a stock and a trigger having a notch at its rear end, of a locking member slidably mounted upon the stock and engageable in its forward position with the notch of the trigger, said locking member including a portion resting upon the stock and adapted to be gripped by the fingers of the operator, and a spring resisting the forward movement of the locking member and urging the locking member rearward to an inoperative position.

35. In a gun, the combination with a stock, a trigger and a trigger guard extending beneath the trigger, then bent inwardly toward the stock and then extending along the stock, said inwardly bent portion of the guard being slotted, of a sliding locking member mounted rearward of the trigger and engageable when in its forward position to lock the trigger from actuation, said locking member including a vertical web extending through the slot of the trigger guard, and a web extending transversely at right angles to the vertical web and extending across the rear edge of the same and the rear face of the trigger guard and then extending longitudinally along the horizontal face of the trigger guard into a position to be gripped by the fingers of the operator.

36. In a gun, the combination with a trigger, of trigger locking mechanism actuated by the recoil of the gun to lock the trigger in its raised position, and a freely slidably, rearwardly extending hand grip adapted to be gripped by the hand of the operator and operatively connected to the trigger locking mechanism whereby to cause the trigger locking mechanism to release the trigger upon the rebound of the gun from its recoil.

37. A single trigger mechanism for double barreled guns including sears, one for each barrel, a single trigger having a notch at its rear end, a sear tripping member in operative engagement at all times with the trigger and manually movable into a position to

operatively engage with either sear, a sear tripping member automatically movable into position beneath both of the sears upon a single actuation of the trigger, and a recoil operated locking member freely slidably into and out of engagement with the notch of the trigger, said member having a portion extending rearward of the trigger and adapted to be engaged by the hand of the operator.

38. A single trigger mechanism for double barreled guns including sears, one for each barrel, a single trigger having a longitudinal notch at its rear end, a sear tripping member in operative engagement at all times with the trigger and manually movable into a position to operatively engage with either sear, a sear tripping member automatically movable into position beneath both of the sears upon a single actuation of the trigger, a trigger guard having a rearward extension parallel to the lower face of the gun stock, a recoil operated locking member disposed immediately behind the trigger and slidably into and out of engagement with the notch thereof, said locking member having a rearward extension resting upon the face of the rearward extension of the trigger guard and adapted to be gripped by the hand of the operator.

39. A single trigger mechanism for double barreled guns including sears, one for each barrel, a single trigger having a longitudinal notch at its rear end normally disposed below the lower tang of the gun, a sear tripping member in operative engagement at all times with the trigger and manually movable into a position to operatively engage with either sear, a sear tripping member automatically movable into position beneath both of the sears upon a single actuation of the trigger, a trigger guard extending beneath the trigger, then angularly bent and extending along the lower tang of the gun, a recoil operated locking member slidably mounted upon the face of the lower tang and movable into or out of engagement with the notch of the trigger, said member having a portion passing through a slot in the angular part of the trigger guard and a rearward extension slidably engaged with the rearward extension of the trigger guard.

40. A single trigger mechanism for double barreled guns including a plurality of sears, a single trigger, the rear end of which is formed with a longitudinally extending notch, a selector resting upon the trigger and manually movable from a safety position into a position to engage either sear to effect the discharge of either barrel, a lower tang through which the trigger passes, a trigger guard extending beneath the trigger, then bent toward the tang and having a rearward extension resting upon the tang,

a recoil operated locking member slidably mounted upon the lower face of the tang rearward of the trigger and movable into or out of engagement with the notch thereof, said locking member having a rearward extension passing loosely through the angular portion of the trigger guard, and extending along the extension of the trigger guard into position to be engaged by the fingers of the operator, the rear end of said extension having sliding engagement with the like end of the extension of said guard.

41. A single trigger mechanism for double barreled guns including a lower tang, a pair of sears, each having an inwardly projecting lug, a trigger movable through a slot in said tang, the rear end of the trigger being notched at its lower corner, a selector supported by the trigger and longitudinally movable beneath said sears and having oppositely projecting lugs offset from each other whereby in one position one of the lugs on the selector will engage one of the sear lugs but the other lug will be out of engagement with its corresponding sear lug, and in a second position the last named sear lug will engage with the corresponding lug on the selector but the other selector lug will be out of engagement with the corresponding sear lug, a recoil operated locking member slidably mounted upon the face of the tang rearward of the trigger and engageable with the notch in the trigger when the trigger is raised to thereby lock the trigger, a trigger guard extending beneath the trigger and having an extension disposed along the face of the lower tang, said locking member having a rearward extension slidably mounted upon the face of the extension of the trigger guard and slidably engaged therewith and adapted to be grasped by the hand of the operator.

42. A single trigger mechanism for double barreled guns including an upper and a lower tang, a tang screw passing through said tangs, a plurality of sears, a trigger passing through the lower tang and having a longitudinal notch at its lower rear corner, a selector resting upon the trigger and moving from a safety position to a position to engage either sear to effect the discharge of either barrel, a slide mounted upon the face of the upper tang, manually actuatable, operative connections between the slide and the selector, means for yieldingly detailing the selector in any shifted position, a trigger guard extending beneath the trigger and then extending rearward along the lower tang, said trigger guard being formed with a vertical slot, a locking member slidably mounted upon the under face of the lower tang and held in engagement therewith by the tang screw, said locking member being shiftable forward into engagement with the

notch of the trigger when the trigger is in its raised position or shiftable rearward out of such engagement, said locking member having a portion thereof extended along and parallel to the face of the trigger guard and adapted to be gripped by the hand of the operator, and means for slidingly engaging the rear end of the rearward extension of

the locking member with the rear end of the extension of the trigger guard. 10

In testimony whereof I affix my signature in presence of two witnesses.

HARTWELL L. WILLIAMS. [L. S.]
